FEATHER RENOVATING APPARATUS

Filed Aug. 9, 1926

UNITED STATES PATENT OFFICE

JOHN C. BRUBAKER, OF LOS ANGELES, CALIFORNIA, ASSIGNOR OF ONE-HALF TO L. F. CASWELL, OF LOS ANGELES, CALIFORNIA

FEATHER-RENOVATING APPARATUS

Application filed August 9, 1926. Serial No. 128,272.

This invention relates to apparatus for renovating feathers. It is a fact that pillows and mattresses stuffed with feathers are sometimes used for years without being cleaned, and the feathers become very dirty and unsanitary. It is the present practice to remove such feathers from time to time from the pillows or mattresses and clean the same. The object of this invention is to provide a simple apparatus for effecting the renovation, cleaning and sterilizing of such feathers.

One of the objects of the invention is to provide an apparatus which will have sufficient capacity to perform the renovating operation upon a large scale, that is to say, which will enable large quantities of feathers to be treated and renovated within a short time.

Another object of the invention is to provide an apparatus of this kind in which the feathers can be handled largely by pneumatic means.

One of the objects of the invention is to provide means for steaming the feathers without imparting too much moisture to them, thereby producing a fluffy effect in the feathers.

A further object of the invention is to provide renovating apparatus constructed in units, facilitating the renovating of the feathers in batches, that is to say, to provide apparatus which will enable the feathers of each order or consignment to be treated independently and without mixing the same with other feathers.

Further objects of the invention will appear hereinafter.

The invention consists in the novel parts and combination of parts to be described hereinafter, all of which contribute to produce an efficient feather renovating apparatus.

A preferred embodiment of the invention is described in the following specification, while the broad scope of the invention is pointed out in the appended claims.

In the drawing:

Figure 1 is a side elevation of a renovating apparatus embodying my invention.

Figure 2 is a vertical section taken about on the line 2—2 of Fig. 1.

In using the apparatus, the feathers are first beaten or agitated so as to remove all dirt or chaff adhering to them; after this is accomplished, the feathers are then sterilized by subjecting them to the action of steam, and preferably steam and hot air simultaneously; after the sterilizing operation, the feathers should be dried. My apparatus for accomplishing this is preferably constructed of units, each unit being constructed so that it is capable of performing any of these operations on the feathers. In addition to this, the units are connected up by a pneumatic system so that the feathers can be handled completely through the agency of pneumatic ducts or pipes. There may be as many units as desired.

Referring to the drawing, which illustrates an embodiment of my apparatus, 1 indicates an elongated casing carrying three units 2, 3 and 4. These units are substantially alike in construction and one of them is shown in vertical section in Fig. 2. Each unit consists of a holder for the feathers, preferably in the form of a drum 5, and in this drum there is mounted an agitator in the form of a beater 6 carried on a rotatable shaft 7. This beater 6 has a plurality of substantially radial arms carrying cross-bars or slats 8 which stir up the feathers within the drum and keep them agitated.

Each drum is provided with a jacket 9 to enable the same to be highly heated. The heat is imparted to the interior of the jacket through a steam coil 10 corresponding to each unit and provided with its corresponding valve 11 for controlling the flow of steam to it.

Each holder is provided with a hand-filling opening 12 (see Fig. 2) closed by a cover 13 which may be held closed by means of fastening bolts with wing nuts 14. At the bottom 15 of each unit, a gutter or pocket 16 is provided, and in this pocket the dirt or chaff accumulates when the feathers are being cleaned. This pocket is closed by a swinging door 17 which may be opened at will to permit the dirt and chaff in the pocket to

descend into a receiver 18. This receiver is connected with a pneumatic pipe 19 which leads to a suction fan 20 that carries off the chaff and dirt and delivers the same into a bin 21.

5 Each unit is provided with an outlet 22 disposed on its upper side, and this outlet is preferably in the form of a suction hood 23 connected to a suction fan, so that air within the drum can be drawn upwardly through a screened opening, that is to say, through an opening provided with a screen 24. This screen is preferably in the form of a slide 25 which can be withdrawn when desired to 10 clean the same (see Fig. 2).

I provide means for subjecting the feathers to the action of steam and hot air simultaneously. For this purpose, at one side of each unit I provide an air box 26. Each air box 20 is provided with a horizontal steam pipe 26^a having perforations 27 on its inner side. The flow of steam through these individual steam pipes is controlled by individual valves 28 (see Fig. 1), which admit steam from the 25 steam supply pipe 29.

When the steam is admitted to the interior of the drum through the perforations 27, I also admit hot air to the air box. This air is preferably drawn into the air box through 30 an air pipe 30 corresponding to each air box. These pipes 30 lead from the jacket space 9 of each unit, which is highly heated by the steam coils. In this way, the air which is drawn into the air boxes is highly heated. 35 The function of the heated air is to enable the steam to sterilize the feathers without producing condensation of moisture upon them. In this way, although the feathers are sterilized, they are maintained in a fluffy condition. The escaping steam draws the air 40 into the drum through the air box.

I shall now describe the pneumatic system by means of which the feathers may be introduced into the different units and moved from any unit to any other unit. In this 45 connection, it should be understood that at times it may be desired to perform different operations of cleaning, sterilizing and drying in the different units in succession, instead of carrying out the three operations in one unit.

In order to supply the feathers to the different units by pneumatic means, I provide each unit with an inlet 32 (see Fig. 2), and these inlets are all connected to a trunk 33 55 connected with the delivery side of a blower fan 34. The feathers may be admitted into a suction nozzle 35 carried at the upper end of a vertical pipe 36 which leads down and is connected by a branch 37 to the suction side 60 of the blower 34. When the valve 38 in this pipe 36 is opened and the nozzle 35 introduced into a pillow or mattress containing feathers, the suction will draw the feathers down the pipe 36 and through the fan 34 and 65 through the trunk 33. Each of the pipes 32

is provided with a valve 39, and by closing or opening the valves 39, the feather-carrying current of air can be directed into any one or all of the units. At the same time that the current of air carrying the feathers is directed into the units, air is withdrawn from the units through the suction hoods 23. This is accomplished by means of a suction fan 40 connecting to a suction trunk 41, from which the suction pipes 22 branch off. This suction trunk 41 is provided with valves 42 and similar valves 43 are provided in the suction pipes 22. By closing and opening these valves, air can be withdrawn from any one or all of the hoods 23.

The pneumatic system also affords means for moving the feathers from one unit to another unit. In order to accomplish this, each unit is provided with an outlet 44 at its under side (see Fig. 2), closed by a door 45 controlled by a lever 46 and a link 47. When these doors 45 are opened, they will permit a current of air to flow out through the drum and through a suction outlet 48 corresponding to each unit. These outlets 48 connect to a main or trunk 49 (see Fig. 1), and adjacent each of the pipes 48 the trunk 49 is provided with valves 50 which may be manipulated so as to enable suction to be developed through any one or all of the outlets 44. This suction main or trunk 49 connects to the suction inlet 37 of the blower 34 and may be cut off from the same by a valve 51. Evidently, if the valve 38 is closed and the valve 51 opened, a suction can be created from any unit through the fan 34, and feathers can be in this way carried on air through the fan 34 and into the trunk 33, from which they can be directed by means of valves 52 in this trunk into any one of the delivery pipes 32, which will deliver the feathers into the units. Each of the air pipes 30 for the air-boxes is provided with its individual valve 54, which controls the flow of air through it.

Air is circulated over the steam coils 10 and up through the jackets 9 by means of an exhaust fan 31 with branch pipes 31^a, 31^b, 31^c, leading to a trunk 31^e from the individual jackets and provided with valves 31^d for controlling the same. This air is admitted to the space over the coils through an inlet opening 10^a.

Sometimes it may be desired to reverse the direction of flow of air through the entire system. In order to enable this to be accomplished at will, I attach the end of the trunk 33 to the delivery side of a blower fan 55, which may be driven by a belt 56, and provided with a suction inlet 57 opening from the atmosphere.

After the treatment of the feathers is completed in the apparatus, they may be delivered through a delivery pipe 58 at a station 59, where they can be returned to the pillows or mattress from which they were removed.

This pipe may be provided with its individual valve 60, which enables it to be cut off at will from the trunk 33.

Referring again to the construction at the air boxes 26, each of these air boxes is provided with a cover 61 which forms the outer end of a drawer 62. This drawer at its inner end carries a screen 63 which is located near the inner face of the wall of the drum and excludes the feathers from the air box. The body of this screen may be about on a line with the axis of the steam pipe 26 and it may have a pocket around the rear side of the pipe. This enables the screen to be brought nearer to the inner face of the drum.

In operating the apparatus, the feathers may be completely treated in one unit or they may be treated in succession in the different units. For example, if the batch of feathers being treated is a small batch, one unit can be used for effecting the operation of the cleaning of the feathers, for sterilizing the feathers thereafter, and for drying the feathers after they have been sterilized.

The feathers may be placed by hand in any one of the units by opening its charging door 13. However, if desired, the feathers may be supplied to any one of the units by the pneumatic system. In this case, the feathers are drawn out of the pillow or mattress by the nozzle 35 and passed down the suction pipe 36 and through the branch 37 into the blower fan 34. If it is desired to deliver feathers into the left-hand unit through its pipe 32, the valve 39 corresponding to this pipe will be opened and the adjacent valves 52 in the trunk 33 will be closed. This will cause the current carrying the feathers to flow down the pipe 32 which corresponds to the left unit and will deliver the feathers into the interior of the drum (see Fig. 1). At the same time, the suction fan 40 should be operated so as to create a suction in the trunk 41. The valves 42 in this trunk 41 should be closed and the valve 43 opened which corresponds to the hood 23 of the first unit. In this way, the action of the current carrying the feathers into the unit is assisted by withdrawing the air within the unit through the screen 24. In the same way, by properly setting the valves of the pipe system, feathers can be delivered from any renovator unit into any other unit.

In the treatment of the feathers, they are first cleaned while being agitated by the beaters 6, the dirt from them accumulating in the trough or pocket 16. When the door 17 is opened, and suction exerted in the suction pipe 19, this dirt or chaff will be withdrawn by the suction fan 20 and delivered into a bin 21. Suitable means, not illustrated, may be provided for latching the stems 47 in the closed and open position of the door 45.

After being cleaned, the feathers may be

sterilized in the same unit or removed by the pneumatic system to the next unit for sterilizing. The sterilizing is accomplished by the steam admitted through the pipe 26, and at the same time hot air is drawn in through the air boxes 26 through the pipes 30. The air passing through the pipes 30 is first heated by passing through the jacket space 9.

After being sterilized, the feathers may be dried in the same unit, or removed for drying to the next unit by the pneumatic means. When drying them, they are agitated in the drum while the drum is maintained in a heated state by its corresponding steam coil.

The feathers are handled in batches, each batch or "order" being treated in one of the units and kept separated from other batches that are being treated.

In cleaning the feathers, while the chaff is collecting in the gutter 16, suction is maintained through the hood 23 to carry off the dust that is being removed from the feathers.

It will be noted that the pneumatic means for withdrawing the feathers from the drum operates independently of the agitator. That is to say, it is not mechanically connected with the agitator and it is driven independently of the agitator.

The air which passes into the renovator is not merely permitted to flow in, but is injected from the exterior.

It is understood that the embodiment of the invention described herein is only one of the many embodiments this invention may take, and I do not wish to be limited in the practice of the invention, nor in the claims, to the particular embodiment set forth.

I claim:

1. In a feather renovator, the combination of a drum, a rotary agitator for the feathers mounted within the drum, said drum having an inlet for the feathers and having a screened outlet, means for driving the rotary agitator, an exhaust fan for withdrawing air through the screened outlet to draw feathers into the drum through the said inlet, and means for driving the exhaust fan independently of the agitator.

2. In feather renovating apparatus, the combination of a drum having a suction hood over the same, a screen associated with the hood, agitating means in the drum, means for withdrawing air from the drum through the hood and screen, means for driving said last named means independently of the agitator, and means for admitting a current of air carrying feathers into the drum.

3. In feather renovating apparatus, the combination of a plurality of holders for feathers, suction pipes connecting with the upper sides of said holders and having a suction fan connected therewith to withdraw air from any of the said holders, valves in the said suction pipes enabling the suction to be

exerted at any one of the said holders, and inlet pipes with valves for controlling the same to admit currents of air carrying feathers to any one of the said holders.

5. In feather renovating apparatus, the combination of a plurality of holders, screened hoods corresponding to the different holders, suction pipes leading from the said hoods with a suction fan for withdrawing air through the screens, valves associated with the pipes to enable the suction to be exerted through any one of the hoods, delivery pipes leading to the different holders with a blower for forcing an air current carrying feathers into the different holders, and valves associated with the last-named pipes to enable the feather-carrying current to be directed into any one of the holders while the suction is exerted through its hood.

10. 5. In feather renovating apparatus, a drum for the feathers, an agitator for the feathers within the drum, an air-box at the side of the drum, a steam-pipe extending through the air-box and having perforations for admitting steam into the interior of the drum, a drawer in the air-box having a cover for closing the same and having a screen at its inner end fitting around the said pipe so as to exclude feathers from the interior of the air-box, and means for admitting hot air to the interior of the air-box.

15. 6. In feather renovating apparatus, the combination of a holder for the feathers in the form of a drum having a jacket space over its upper side, heating means removed from the jacket space, and means for forcing air over the heating means and thence through the jacket to heat the drum.

20. 7. In feather renovating apparatus, the combination of a holder for the feathers in the form of a drum having a jacket space over its upper side, heating means removed from the jacket space, means for forcing air over the heating means and through the jacket to heat the drum, and means for injecting steam and hot air to the interior of the drum.

25. 8. In apparatus of the kind described, the combination of a feather renovator having a plurality of drums to receive the feathers, agitating means in the drums, each of said drums having an outlet for the feathers, with a door corresponding to each outlet, a trunk connected with the said outlets, a blower having its suction side connected with the said trunk, a trunk connected with the blast side of the said blower and having a plurality of branches connecting with the said drums, valves in said last named trunk and said branches, and valves associated with the first named trunk corresponding to the said outlets, said valves cooperating to enable the blower to withdraw feathers from any one of said drums and deliver the same to any other of said drums.

30. 9. In apparatus of the kind described, the

combination of a feather renovator having a pair of drums to receive the feathers, agitating means in each drum, each of said drums having an outlet for the feathers with a door corresponding to each outlet, a trunk connected with the said outlets, a blower having its suction side connected with the said trunk, a trunk connected with the blast side of the said blower and having a pair of branches connected with the said drums, valves in said last named trunk and said branches, and valves associated with the first named trunk corresponding to the said outlets, said valves cooperating to enable the blower to withdraw feathers from either of said drums and deliver the same to the other of said drums.

Signed at Los Angeles, Calif., this 2nd day of August, 1926.

JOHN C. BRUBAKER.
